UNITED STATES PATENT OFFICE.

ELMER AMOS McARTHUR, OF FLINT, MICHIGAN.

FURNACE UTILIZING FORCED DRAFT.

Application filed February 16, 1927. Serial No. 168,745.

This invention relates to an improvement in furnaces utilizing forced draft.

The object of the invention is to provide a furnace of this character which when associated with a boiler will maintain a substantially constant pressure of steam in the boiler, the steam pressure being utilized to control the operation of novel instrumentalities which regulate the amount of air flowing into the furnace, the amount of air flowing into the furnace being adapted to control a novel set of dampers associated with the grate to regulate the passage of air through the grate and this same set of dampers controls the operation of an automatic stoker associated with the furnace. In general the steam pressure controls the forced draft passing through the grate and the forced draft controls the amount of fuel supplied to the grate or combustion chamber.

Other objects and advantages reside in certain novel features of the construction, arrangement and combination of parts which will be hereinafter more fully described and particularly pointed out in the appended claims, reference being had to the accompanying drawings forming a part of this specification, and in which:—

Figure 1 is a view partly in side elevation and partly in longitudinal vertical section showing a furnace and boiler assembly having the present invention organized therewith,

Figure 2 is a fragmentary view similar to Fig. 1 but illustrating only the baffle arrangement, grate, stoker and stoker control,

Figure 3 is a fragmentary detail view illustrating the operation of the stroke-changing mechanism of the stoker control,

Figure 4 is a perspective view showing the automatic baffle or damper arrangement together with the stoker and stoker control means,

Figure 5 is a view partly in elevation and partly in section showing the mechanism employed to permit the steam pressure to control the amount of air supplied to the grate or chamber below the grate, and

Figure 6 is a fragmentary vertical section showing the resilient connection between a lever and an operating shaft.

Referring to the drawings the numeral 1 designates generally a furnace which has a grate 2 made up of closely spaced bars 3 and rather widely spaced bars 4. It is to be understood, however, that the construction of

the grate may be varied without departing from the present invention. Below the grate 2 a chamber 5 is provided, this chamber being substantially closed, the only outlet of the chamber being through the combustion chamber 6 by way of the grate 2. Water tubes 7 of the boiler 8 extend through the upper portion of the combustion chamber.

Fuel is supplied to the grate from a hopper 10 which has a chute 11 extending down to a fuel supply opening 12, the opening 12 being located opposite a lateral branch 13 of the chute 11 in which branch a ram 14 of a stoker, designated generally at 15, operates. The stoker 15 may be of any suitable or conventional type and in the present application a Jones type of stoker is shown. As illustrated to advantage in Fig. 2 the ram 13 is carried at the forward end of a piston rod 16 connected to a piston 17, the piston 17 operating in a cylinder 18. Steam or other motive fluid is supplied to the cylinder under the control of valve mechanism, not shown, and this steam or motive fluid operates to reciprocate the piston 17 and consequently the ram 13. The movement of the ram 13 back and forth results in the feeding of the coal or the fuel from the chute 11 onto the grate.

In the pit 20 below the boiler room a boxing 21 is provided and to this boxing 21 air under a substantially constant pressure is supplied. Any suitable means may be provided for supplying the air under constant pressure to this boxing 21 and for the sake of illustration such a means is shown as a motor-operated fan 22. A conduit 23 leads from the boxing 21 into the chamber 5 and the passage of the air through the conduit 23 into the chamber 5 is controlled by means of a damper 24 mounted on a shaft 25 rotatably supported in bearings provided therefor in the conduit 23.

Within the chamber 5 an automatic baffle arrangement is provided for controlling the amount of air and the distribution of air which passes through the grate. This baffle arrangement comprises a shaft 30 rotatably mounted in suitable bearings provided therefor. Adjacent the ends of the shaft discs 31 are fixed thereto. These discs have arcuate slots 32 therein with which bolts and nuts 33 co-operate, the bolts and nuts 33 serving to adjustably secure to the discs 31 a main baffle 34. The baffle 34 includes side bars 35 rotatably mounted on the shaft 30 and carrying a fixed body plate 36 and a swinging wing or plate

37, the plate 37 being hinged, as at 38, to the plate 36. It is the bars that are adjustably fastened to the discs 31 by the bolts and nuts 33 and this permits the main baffle or damper 5 to close at the desired time inasmuch as it may be adjusted angularly relative to the shaft 30 and the discs 31. A swinging vane 40 is provided and is pivotally connected, as at 41, to the lower ends of the arms 42, the arms 10 42 being loosely mounted at their upper ends on the shaft 30. These arms 42 are connected to the bars 35 by means of longitudinally adjustable links 43, the sections of the links 43 being fastened or otherwise suitably connected 15 to the bars 35 and arms 42 and being adjustably clamped to each other by means of bolts and nuts 44 extending through aligned slots 45 in the sections of the link. Similar, though longer, links 46 are provided for connecting the vane 40 with the pivoted section 37 of the main baffle, the links 46 being longitudinally adjustable though rigid in any adjustment and having their ends pivotally connected to the section 37 and vane 40. 20 Means is provided tending to maintain the pivoted section 37 in an open position, that is, in the position shown in Fig. 1, and this means preferably comprises a pair of rods 50 having turnbuckles 51 incorporated therein 25 to make the rods of adjustable length. The rods 51 have their upper ends connected, as at 52, to the section 37 and have their lower ends connected to springs 58, the springs 58 being in turn connected by means of links 59 30 to the arms 42.

With the arrangement thus far described the blast that blows in through the conduit 23 encounters the main baffle 34 and when this blast is at its height it will swing this main baffle 34 upwardly from the dotted line position of Fig. 2 to the full line position of Fig. 1. This results in the interposition of the baffle 34 between the grate and the blast so as to reduce to some extent the amount of air 40 passing through the grate. Then if the strength of the blast is maintained it will act on the vane 40 to swing the same from the full line position shown in Fig. 1 to the full line position shown in Fig. 2, thereby completely 45 closing off that section of the grate made up of the closely spaced bars 3 and causing all the blast of air to pass through the lower portion of the grate made up of the grate bars 4.

The position of the baffle arrangement in 55 the chamber 5 regulates or controls the operation of the stoker and this control or regulation is effected by utilizing the motion of the discs 31 to automatically change or vary the stroke of the ram 13 of the stoker. In carrying out this purpose the discs 31 are provided with camming ribs 60 co-operable with rollers 61 provided at the ends of the levers 62, the levers 62 being fixed to a shaft 63 having a slotted arm 64 secured thereto and connected 60 with the lower end of a connecting rod 65 by

means of a pin 66 operating in the slot of the arm 64. The hand wheel operated turnbuckle 67 is interpositioned between the sections of the rod 65 to provide variation in length of the link. The upper end of this rod 65 is connected to a bell crank lever 68 fulcrumed, as at 69, adjacent the outer end of a hand lever 70. The hand lever 70 is fixed to a shaft 71 rotatably mounted in suitable brackets and disposed adjacent to a quadrant 75 72. This quadrant has a single notch 73 with which a spring-pressed detent 74 is adapted to engage. The detent 74 is controlled from the bell crank lever 68 through the medium of a wire or wire-like rod 75. The shaft 71 80 has an arm 76 loosely mounted thereon and resiliently connected therewith by means of a spring 77 having one end anchored, as at 78, in the shaft 71 and having its opposite end engaged with the arm 76. The outer end of 85 this arm 76 carries a roller 79 and the roller 79 is engaged with the underside of a pivoted plate 80 having a yoke 81 at one end pivotally mounted, as at 82, on a stationary bracket 83. The bracket 83 is formed with a longitudinal slot 84 extending entirely through the same. In this slot a depending bar 85, which is rigidly connected with the ram 13 of the stoker, operates. The bar 85 may be guided in a back and forth movement in the slot of 90 the bracket by means of a lateral pin 86 operating in a guide slot 87. A wedge 88 is positioned for sliding movement up and down in the slot 84 of the bracket 83, the wedge being constrained to sliding movement and 95 held against displacement from the slot 84 by means of the pin 89 operating in a slot 90 of the wedge. The bottom or large end of the wedge preferably has a roller 92 mounted thereon and engageable with the pivoted 100 plate 80.

With this construction when the baffle arrangement is entirely open, as shown in dotted lines in Fig. 2, the wedge member 88 is in its lowest position in the slot 84 and the ram 13 of the stoker is reciprocated on its longest stroke and is charging the furnace with fuel at its greatest capacity. As the baffle arrangement closes, the cams on the discs 31 swing the lever arms 62 to release 110 the detent and force the hand lever 70 in a clockwise direction as viewed in Figs. 1, 2 and 3, whereby the wedge member 88 is elevated and the stroke of the stoker is shortened so that less fuel is delivered onto the 115 grate of the furnace.

The boiler pressure is utilized to control the damper 24 and consequently to control the amount of the blast blown through the conduit 23 into the chamber 5 and in carrying out this purpose the pipe line 100 leads from the steam space of the boiler and connects with a sliding valve casing 101. The sliding valve casing 101 has a partition 102 therein and in the partition ports 103 and 130

104 are provided. The valve casing has its outlet coupled to a pipe 105 having a branch 106 leading into the lower end of a cylinder 107 and a branch 108 leading into the upper 5 end of this cylinder. A rotary valve, designated generally at 109, is incorporated in the branch 106 and comprises a casing 110 having a partition 111 formed with an inlet port 112 and an inlet port 113. A single outlet 10 portion 114 is provided and leads to the cylinder 107. An exhaust or vent to the atmosphere is also provided and is designated at 115, this exhaust or vent to the atmosphere being controlled by a rotary plug valve 116. 15 Within the casing 110 a main valve body 117 is provided and has a diametrical port 118 and a radial port 119, the port 118 being designed to successively register with the ports 112 and 113 and the port 119 being designed to register with the vent 115 in certain 20 phases of the operation. The port 118 is in registration with the outlet port 114 at all times. The branch 108 has a valve casing 120 incorporated therein, the valve casing 25 120 having a partition 121 formed with a single inlet port 122. This casing 120 also has an outlet port 123 and a vent 124 controlled by a rotary valve 125. Within the casing 120 a main valve body 126 is rotatably 30 fitted, the main valve body 126 having a diametrical port 127 always in registration with the outlet port 123 and adapted to be registered with the inlet port 122 or to be blocked by the partition 121. A radial port 128 is also 35 formed in the main valve body 126 and leads from the port 127 out through the periphery of the valve body, this port 128 having been designed to register with the vent 124 in certain 40 phases of the operation. The vent 115 of the valve 109 has a hand-controlled valve 130 incorporated therein and designed to vary the bore of this vent so as to accelerate or retard the escape of the steam therethrough. This valve 130 has an arm 132 fixed thereto 45 and connected with a link 133, the link 133 also being connected to a lever 134^a. The upper end of the link 133 is connected to the lever 134^a fulcrumed on a clamp 135 fixed on the branch 108 of the steam line. The 50 lever 134^a is connected by a rod 136 or other motion transmission means to a suitable controlling lever at any desirable point. The rotary valve body 117 of the valve 109 has an arm 140 fixed thereto, this arm 140 being 55 pivotally connected to the lower end of a lever 141 fulcrumed, as at 142, on a link 143 carried by the cylinder 107. This same lever 141 is connected by means of a link 145 with an arm 146 fixed to the valve 126. The lever 141 has 60 a pin and slot connection 147 with a shiftable rod 148, the shiftable rod 148 being connected to a sliding valve 149 traveling over the partition 102 and having ports 150 and 151 65 registrable with the ports of the partition. The opposite end of the shiftable rod 148 is provided with a yoke 152, the arms of which are connected by a cross pin 153 which operate in a cam slot 154 formed in a gear segment 155 fulcrumed, as at 156, on a frame 157. The gear segment 155 has an arm 158 integral therewith and carrying a counter-weight 159. This arm 158 extends between 70 rollers 160 provided on the upper end of a piston rod 161 extending upwardly from a piston 162 operating in the cylinder 107. A second gear segment 163 meshes with the gear segment 154, the gear segment 163 being pivotally mounted, as at 164, on the frame 157. The gear segment 163 also has an arm 165 integral therewith, the arm 165 being connected by means of a connecting rod 166 with an arm 168 fixed to a gear 169 pivotally mounted on the conduit 23 and meshing with the gear wheel 25 which is fixed to the axle 80 of the damper. 85

The rod 148 is releasably held in several of its adjusted positions by means of a latch 170 co-operable with notches 172 in the rod 148. The latch 170 is fixed to a sliding block 174 mounted in a bracket 175 carried on the frame 157, the block 174 having a stem 176 slidably fitted through a guide bar 178 of the bracket 175 and carrying a nut 179 to limit the downward movement of the sliding block 174. A spring 180 encircles the stem 176 and is 90 compressed and arranged to force the block 174 downwardly. The lower end of the block carries a roller 181 engaging with a cam 182 formed on the gear segment 155. The pin 183 which operates in the cam slot 154 has a 95 rod 185 pivotally connected thereto, the rod 185 extending loosely through an opening 186^a provided in an arm 186 formed on the gear segment 163. The upper end of this rod 185 is threaded and has a nut 187 adjustably mounted thereon, the nut engaging the upper end of the coil spring 188 and encircling the rod and having its lower end abutting a rounded washer 189 loosely mounted 100 on the rod 185 and engaging the arm 186. 105

Referring more particularly to Fig. 5, it will be seen that the various elements which are operated through steam pressure are in such a position that steam from pipe 100 passing through ports 151 and 103 enters 110 pipes 105 and 106 and is acting on the under face of the piston 162 thereby maintaining the piston in its uppermost position. When the damper 24 is first turned to horizontal 115 position and air is permitted to enter the chamber 5 of the furnace which is below the grate, the baffle 34 is in the dotted line position shown in Fig. 2. In such position the cam member 88 is in its lowermost position, shown in Fig. 3, whereby the ram 13 of the 120 stoker is permitted its full working stroke. The pipe 108 is exhausting through the port 127 and port 128 through the valve 125 and through the restricted vent 124 whereby the 125 piston 162 is cushioned on its up stroke. 130

With the damper 24 open, a full force draft is had which acts on the plate 40 and plate 36 thereby elevating the frame 34 to its uppermost position and closing the baffle 37, as indicated in full lines in Fig. 2. The arm 76 is moved to its most elevated position, raising the member 80 and thereby forcing the cam 88 into the position shown in Fig. 2, thus limiting the stroke of the ram 13. Since the major portion of the air is cut off to the grate 2, and the ram 13 is limited in its stoking operation, the fire bed will naturally be decreased in density so that the pressure of the steam is not sufficient to maintain the piston 162 in its most elevated position against the weight 159, said piston will fall thereby closing the port 118 with the valve 117 and cutting off communication between the sections of the pipe 106 at opposite sides of the valve 117. The port 119 will then register with the discharge port 115 and steam from cylinder 107 below piston 162 will be exhausted. At this time the port 107 will register with the port 122 thereby admitting steam through pipe 108 through cylinder 107 above piston 162. As the piston 162 is lowered, arm 158 will fall causing the cam member to engage the roller 181 raising the member 174 and likewise the latch 170 from the notch 172, and as the rod 148 is moved in the direction indicated by the arrow in Fig. 5, the latch 170 will drop into notch 173 and maintain rod 148 against further movement. As the lever or arm 158 moves downwardly the segmental gear 155 being in mesh with the segmental gear 163 will actuate the gear 163 moving the arm 165 and likewise arm 168 downwardly rocking the gear 169. This causes rotation of gear 25 and actuation of the damper 24 to the dotted line position shown in Fig. 5. Since the air draft is cut off from the pipe 23 the baffle 34 will no longer be sustained in its elevated position and will fall to the dotted line position shown in Fig. 2, thereby permitting air to pass through the chamber 5 around the plate 37 and through the opening in the frame or baffle 34 and through the grate 2. At this time the lever 76 is moved downwardly thereby permitting the cam 88 to be moved from the bracket 83 so that the ram 13 of the stoker will be permitted its full power stroke, thereby placing the greater quantity of coal on the grate while at the same time air passes up through the grate for stimulating the fire which will thus increase the pressure of the steam in the boiler.

I claim:—

1. The combination with a boiler having a grate, stoking means for supplying fuel to the grate, a chamber below the grate, means for supplying air under pressure to the chamber, of a baffle arrangement in the chamber having surfaces exposed to the blast of air whereby the baffle arrangement is automatically controlled to regulate the amount of air passing to the grate in accordance with the draft passing through the chamber, means regulated in its action by the position of the baffle arrangement for controlling said stoking means, a damper for controlling the supply of air to the chamber, and means controlled by the boiler pressure for opening and closing said damper.
2. The combination with a furnace having a grate, a chamber below the grate, means for supplying air under pressure to the chamber, a baffle arrangement in said chamber for regulating the passage of the air to the grate and comprising a main baffle, means for mounting the main baffle for swinging movement, said main baffle having a pivoted section, a vane suspended within the chamber for pivotal movement and disposed across the path of the air to the grate, and means for connecting the vane with the pivoted section of the main baffle.
3. The combination with a boiler having a grate, a chamber below the grate, means for supplying air under pressure to said chamber, a damper for controlling the flow of air to the chamber, means responsive to the boiler pressure opening and closing the damper and comprising a cylinder, a piston in the cylinder, a pair of gear segments, one of the gear segments having an arm operatively connected to the damper, the other gear segment having an arm operatively connected to the piston, a steam line leading to the lower end of the cylinder, a sliding valve incorporated in the steam line, a shifting rod connected to the sliding valve and to one of said gear segments, a rotary valve also incorporated in the steam line and having a valve controlled vent to the atmosphere, and motion transmission devices between the rotary valve and the valve of the vent and the shifting rod for automatically operating the same.
4. The combination with a boiler having a grate, a chamber below the grate, means for supplying air under pressure to said chamber, a damper for controlling the flow of air to the chamber, means responsive to the boiler pressure opening and closing the damper and comprising a cylinder, a piston in the cylinder, a pair of gear segments, one of the gear segments having an arm operatively connected to the damper, the other gear segment having an arm operatively connected to the piston, a steam line leading to the lower end of the cylinder, a sliding valve incorporated in the steam line, a shifting rod connected to the sliding valve and to one of said gear segments, a rotary valve also incorporated in the steam line and having a valve controlled vent to the atmosphere, motion transmission devices between the rotary valve and the valve of the vent and the shifting rod for automatically operating the same.

said steam line having a branch leading into the upper end of the cylinder to provide a cushion, a rotary valve incorporated in said branch, and motion transmission means between the shifting rod and said rotary valve.

5. The combination with a furnace having a grate, a boiler heated by the furnace, a chamber below the grate, means for supplying air under pressure to the chamber, 10 a baffle swingably mounted in the chamber in the path of the air in an open position and adapted to engage the grate when in a closed position for cutting off the air to the

grate, a damper for controlling the flow of air through the chamber, means responsive 15 to the pressure of the boiler for causing opening and closing of the damper thereby controlling the position of the baffle, said baffle being provided with an opening, a valve for closing said opening, a vane swingably connected to the baffle and adapted to be actuated by the air, and means connecting the valve with the vane so that when the vane is moved in one direction the valve will be closed.

ELMER AMOS McARTHUR.
